UNITED STATES PATENT OFFICE.

ERNEST F. FISHER, OF ESSINGTON, PENNSYLVANIA.

STUFFING-BOX.

1,354,544.

Specification of Letters Patent.

Patented Oct. 5, 1920.

Application filed February 27, 1919. Serial No. 279,514.

To all whom it may concern:

Be it known that I, ERNEST F. FISHER, residing at Essington, in the county of Delaware and State of Pennsylvania, a citizen 5 of the United States, have invented or discovered certain new and useful Improvements in Stuffing-Boxes, of which improvements the following is a specification.

My invention relates to improvements in 10 stuffing-boxes or packing glands for machinery shafting, or similar instrumentalities, where differences of pressure (or different media) are to be maintained on opposite sides of a dividing wall, through 15 which the machine part or instrumentality passes. The object of my invention is a stuffing-box or gland which shall be impervious under varying conditions of use, particularly where, in consequence of mal-alignment or conditions of service, the parts are 20 not accurately true.

The invention is illustrated in the accompanying drawing which shows in longitudinal section a stuffing-box of my invention 25 encircling a shaft. The shaft itself is indicated in elevation at 1. The stuffing-box includes first a housing 2, preferably of a general cylindrical shape, supported at one end by the structure to which it is applied, that 30 is to say, the dividing wall or partition through which the machine part passes, and in respect to which different pressures (or different media) are to be maintained, separate one from the other, on opposite sides. 35 To the end of obtaining proper support for this housing it may be conveniently provided with an encircling flange 2^a, at the end where the support is to be had, in order to secure it in impervious engagement upon 40 the structure. It will of course be understood that, instead of being bolted through a flange to a support, this housing may in some cases be cast integral with the supporting body, or be otherwise secured to it. 45 This housing, as will be observed, extends from the support in a direction (when the parts are assembled) longitudinally of the shaft 1.

To the outer or free or unsupported end 50 of the housing 2 is secured a gland case or packing-case 3. This case, as will be seen in the drawing, is of a general cylindrical shape, and housing 2 and packing-case 3 are provided with co-operating flanges 4 and 5, 55 by means of which the packing-case may be secured to the housing, the joint being of

course impervious. It will be noted of the packing-case also, that, when the parts are assembled, it, like the housing, extends longitudinally of the shaft and, in the preferred construction as it is shown in the drawing, the housing encircles and incloses the packing-case, and the packing-case in turn encircles and incloses the shaft. 60

The flanged connection may be formed 65 with such a relatively thin walled channel as 5^a, encircling the shaft, or other provision may be made to increase flexibility at this point, for purposes presently to be indicated. 70

The packing-case 3 is provided at one end with a head (preferably integral) 6, through which is an opening to allow the free passage of the shaft, and it is provided at the other end with a head 7, which takes the 75 form of a nut capable of being screwed into and screwed out of the end of the packing-case, the nut also being provided with an opening for the passage of the shaft. Between these two heads, within the packing-case and between the packing-case and the body of the shaft is a body of packing 8 which, by the screwing in of the head 7, is compressed to afford the desired packing 80 effect. 85

Within the packing-case, adjacent the body of packing 8, and preferably about midway the length of the box is a wick-case 9, preferably of the form sufficiently indicated in the drawings—channel-shaped 90 in cross-section, the channel opening inward, and surrounding the shaft with a sufficient clearance. At one point in the periphery of this wick-case (and, when the shaft extends horizontally, as shown in the drawing, 95 then at the lowermost point in the periphery) is an orifice through the mid-web of the channel, and opposite this orifice is a corresponding orifice through the packing-case. These orifices are provided to allow 100 a wick to extend through. Immediately adjacent and external to the packing-case, and preferably within and part of the housing, is an oil-well 10, and, when the arrangement is as shown in the drawing, the shaft extending horizontally, this oil-well 10 will 105 be so formed that it is disposed immediately beneath the two aligned orifices just mentioned. Screwed into the orifice in the packing-case 3 may be a nipple 11, extending downwardly and beneath the surface of a pool of oil maintained in the oil-well. 110

The parts are assembled as shown in the drawing, a body of oil 12 filling the oil-well, and a wick 13 disposed within the wick-case 9, and extending through the tube 11 into the oil-well. The nipple 11 opens into the oil-well beneath the surface of the pool of oil in the well. The wick-case 9 and the packing 8 are clamped and compressed within the packing-case and about the shaft 1 by screwing in the head 7 of the packing-case. When so assembled and as operation progresses there is an oil feed either by capillary attraction or pressure upon the surface of oil (pressure of the high-pressure side of the 10 dividing wall being exerted upon this surface) through the wick 13 to the surface of the shaft within the packing-case, and so the proper oil supply is afforded to make the packing secure and impervious, and also to 15 lubricate the shaft. An oil-ring 14 may be provided, to convey oil from the oil-well 10 and distribute it upon the surface of shaft 1 at a point adjacent the packing-case from which point it will, as will be understood, 20 creep along the surface to the body 8 of the packing. Instead of this oil-ring another wick-case, similar to the case 9, might, manifestly, be provided.

I have spoken of the material within the 30 wick-case as wick. Of course it will be of any suitable material, fibrous or otherwise, to take up, carry and distribute the oil.

The presence of the tube 11, its lower end sealed beneath the surface of the pool of 35 oil, prevents dirt from being carried to the surface of the shaft.

As shown in the drawings, there is arranged to the left of the stuffing-box or gland a shaft-bearing 15, and, still to the 40 left of the bearing, another packing 16. It will be understood that the lubricant carried by the oil-ring 14 may furnish the necessary lubrication to the bearing 15. On the farther side of the bearing the duct 17 45 may be provided, to bring back any excess of oil into the oil-well.

As illustrated in the drawing, the gland is applied to a rotary shaft. It will be understood that it is applicable to other machine 50 parts extending through a septum wall. For instance, instead of a rotary shaft there might be a reciprocating shaft. In such case, as will be readily understood, the bearing 15 would be dispensed with, and in its 55 place a second packing-case substantially like the packing-case 3 with its contents, might be provided. For such second packing-case a second oiling device like the wick-case 9 and a tube 11, leading into an oil-well, 60 might conveniently be provided, and in such case also the oil-ring 14 might and ordinarily would be found dispensable.

Directing attention to the manner in which the packing case 3 is supported, it is 65 to be noted that it is so supported as to be

flexible; to the end that the packing-case shall in service hug the shaft, even though the shaft be out of line. In the particular embodiment shown (which is exemplary, merely—the invention not being so narrowly limited) the packing case is supported at one end, and at one end only, and this by a flange (itself possessed of some flexibility) to the outer, unsupported end of housing 2. Whatever flexibility the materials afford 75 becomes available, so that the structure accommodates itself to inequalities in the shafting and its alinement (whether due to defects in construction and assembly or—as sometimes is the case with rapidly rotating 80 shafting—due to eccentricity consequent upon high speed). Ordinarily the construction will be such that the flexibility is mainly or entirely in the connecting flanges, and in the walls of the packing-case 3 itself, 85 which are shown to be relatively thin, in comparison with the walls of the housing.

I have intended in this specification to give a typical embodiment of my invention, together with indications of modifications 90 of structure. In this respect my invention is not limited, and I mean to include such modifications as may be made, and still retain the essential features of my invention and be defined in the following claims. 95

I claim—

1. A stuffing-box for shafts including in its structure a cylindrical housing and a cylindrical packing-case arranged within said housing the two said parts being united 100 one to the other through a channeled flange substantially as described.

2. A stuffing-box for shafts including in its structure a housing and a sleeve-like packing case adapted to encircle a shaft and as a packing case complete independently of 105 said housing, but structurally borne by said housing, and extending from said housing longitudinally of the shaft, the extension thereof being otherwise unsupported, said packing case adapted to contain within and between itself and the shaft a body of packing, substantially as described.

3. A flexible stuffing-box for shafts including in its structure a housing adapted 110 to be borne at one end by the structure to which the stuffing-box is applied, and a sleeve-like packing-case carried by the housing at the free end thereof and extending in its turn from the point of support longitudinally of the shaft, the extension thereof being otherwise unsupported, said packing-case being adapted to encircle the shaft and to contain within and between itself and the shaft a body of packing substantially as described. 115

4. A stuffing-box for shafts including in its structure a housing adapted to be borne at one end by the structure to which the stuffing-box is to be applied, and a sleeve- 120

like packing-case arranged within said housing, borne by said housing at the end thereof remote from the point of housing support, and extending from its point of support in 5 opposite direction longitudinally of the shaft, the extension thereof being otherwise unsupported, said packing-case adapted to encircle the shaft and to contain within and between itself and the shaft a body of 10 packing substantially as described.

5. A flexible stuffing-box for shafts including in its structure a housing adapted to be borne at one end by the structure to which the stuffing-box is applied, a sleeve-like packing case borne by said housing and extending from the point of such support longitudinally of the shaft, such extension being otherwise unsupported, said packing-case adapted to encircle the shaft and to contain 15 within and between itself and the shaft a body of packing, an oil-well formed within said housing, and means for carrying oil from said well and spreading it upon the surface of the shaft at a point adjacent such 20 body of packing substantially as described.

6. A stuffing-box for shafts including in its structure a sleeve-like member adapted to encircle a shaft and to contain within and between itself and the shaft a body of packing, a wick-case adapted to be arranged 25 within said sleeve-like member and to encircle the shaft also and to carry a wick and sustain it in contact with the shaft, and an oil-well arranged to receive the end of a 30 wick protruding from said wick-case substantially as described.

7. A stuffing-box for shafts including in its structure a sleeve-like member adapted to encircle a shaft and to contain within and 35 between itself and the surface of the shaft a body of packing, a wick-case adapted to be arranged within said sleeve-like member and adjacent such body of packing, said case being adapted to carry a wick and maintain 40 it in contact with the shaft, an orifice

through said sleeve-like member, an oil-well external to said sleeve-like member, a nipple carried in the orifice through said sleeve-like member, and extending into said oil-well, the parts being so arranged that a wick in place 50 in said wick-case may extend through said orifice, and through the nipple therein, into said oil-well substantially as described.

8. In combination with a shaft-bearing, a stuffing-box including in its structure a 55 sleeve-like member adapted to encircle the shaft and to contain within and between itself and the shaft a body of packing, an oil-well, and means for conveying oil from said well to said bearing and to said stuffing-box substantially as described.

9. In a stuffing-box the combination of a housing borne by the structure to which the stuffing-box is applied and extending from the point of support longitudinally of the 65 shaft, a sleeve arranged within said housing and supported at one end to that end of the housing remote from the point of housing support, the other end of said sleeve being unsupported, said sleeve adapted to encircle 70 the shaft and adapted to contain within and between itself and the shaft a body of packing, a wick-case adapted to be contained within the sleeve adjacent such body of packing and to encircle the shaft, said case 75 being further adapted to contain a wick, said sleeve being provided with an orifice through which may protrude the end of a wick contained in said case, and an oil-well formed in said housing and so arranged that 80 end of the wick protruding through said sleeve may extend into it substantially as described.

In testimony whereof I have hereunto set my hand.

ERNEST F. FISHER.
